GRISWOLD LLP

(57) **CLAIM**

The ornamental design for a train, as shown and described.

DESCRIPTION

FIG. 1 is a front elevational view of a first embodiment of a train;

FIG. 2 is a rear elevational view thereof;

FIG. 3 is a top plan view thereof;

FIG. 4 is a left-side elevational view thereof; a right-side elevational view would be a mirror image thereof; and FIG. 5 is a front/right perspective view thereof; a front/left perspective view would be a mirror image thereof.

FIG. 6 is a front elevational view of a second embodiment of a train;

FIG. 7 is a rear elevational view thereof;

FIG. 8 is a top plan view thereof;

FIG. 9 is a left-side elevational view thereof; a right-side elevational view would be a mirror image thereof; and, FIG. 10 is a front/right perspective view thereof; a front/left perspective view would be a mirror image thereof. The second embodiment has the same contour as the first embodiment (contour lines were removed to not conflict with the stippling).

The dash-dot broken lines represent the bounds of the claimed design, while all other uniformly broken lines are directed to environment and are for illustrative purposes only. Both the dash-dot and uniformly broken lines form no part of the claimed design. The stippling in FIGS. 6-10 represents a contrast of color or a contrast of material.

1 Claim, 4 Drawing Sheets
